UNITED STATES PATENT OFFICE.

WILLIAM RUBEL, OF FLINT, MICHIGAN.

PIPE-CLEANER.

1,316,744.

Specification of Letters Patent. Patented Sept. 23, 1919.

Application filed November 2, 1917. Serial No. 199,861.

To all whom it may concern:

Be it known that I, WILLIAM RUBEL, a citizen of the United States, residing at Flint, in the county of Genesee and State of Michigan, have invented certain new and useful Improvements in Pipe-Cleaners, of which the following is a specification.

This invention relates to smoking pipes and has more especial reference to an improved cleaner therefor.

The invention has for its principal object to provide a smoking pipe cleaner capable of passing a swab or like implement through the smoke passage of a pipe stem in order that all foreign matter therein can be readily and thoroughly removed.

Another and equally important object of the invention is to provide a pipe cleaning device having means thereon for engaging and removing the cleaning swab from the stem of a pipe.

The improvements in the details and arrangement of parts will be apparent from an inspection of the accompanying drawings, in connection with the specific description hereinafter contained, and wherein the preferred embodiment of the invention is disclosed for the purpose of imparting a full understanding of the same.

30 In the drawings:—

Figure 1 is a perspective of the cleaner, and.

Fig. 2 is a fragmental perspective of one end of the same.

35 Having more particular reference to the drawings, the improved cleaning device comprises an elongated body portion 1 formed of either flexible or pliable material and having one end thereof flattened and bifurcated 40 as at 2, while the remaining end is bent to provide a hook element 3. Formed in the intermediate portion of the body 1 is a loop 4, the same serving as means to permit the hanging of the cleaner upon a suitable support when 45 the same is not in use.

In using the improved cleaner, a cleaning swab 5 formed of soft cord or like material is doubled upon itself and engaged in the bifurcated portion 2 of the body 1, where- 50 upon the same is then passed through the

smoke passage of the stem of the pipe which is to be cleaned. When the swab has been passed into the pipe a portion thereof is wound about the loop 4 and, confined between the latter and the straight body portion 1, is securely held in a taut condition between the bifurcated terminal of the body and the loop 4 as it is worked back and forth in the smoke passage of the pipe stem, thereby removing all foreign matter, such as nicotin and the like from the passage. To facilitate the pulling and pushing of the swab through the pipe stem, the portion of the body 1 lying intermediate the hooked terminal 3 and the coil 4 is gripped between the fingers, the latter being prevented from undue slipping owing to their confinement between the coil and hook.

From the foregoing, it will be readily understood that with my improved cleaning element, I provide an extremely simple and efficient device for removing the gummy substance lodged in smoke passages of pipe stems, commonly called nicotin and all other foreign substances therefrom in an extremely rapid and efficient manner. Due to the nature of the material from which the cleaning element is formed, the same may be passed through either curved or straight stems.

Manifestly, the construction shown is capable of considerable modification and such modification as is within the scope of my claim, I consider within the spirit of my invention.

30 I claim:—

A pipe cleaning element including a straight body portion having one end thereof flattened and bifurcated to receive the bight portion of a doubled cleaning swab and 40 having the remaining end hooked, the intermediate portion of the body being looped whereby the swab may be wound thereon and confined between the loop and the body portion to retain the portion of the swab 45 extending between the loop and the bifurcated terminal in a taut condition.

In testimony whereof I affix my signature hereto.

WILLIAM RUBEL.
